UNITED STATES PATENT OFFICE

93,244

DESIGN FOR A MEDAL

Morris Shapiro, Memphis, Tenn.

Application February 17, 1934, Serial No. 50,756

Term of patent 14 years

To all whom it may concern:

Be it known that I, MORRIS SHAPIRO, a citizen of the United States, residing in Memphis, in the county of Shelby and State of Tennessee, have invented a new, original, and ornamental Design for Medals, of which the following is a specification, reference being had to the accompanying drawing, forming part thereof.

I claim:
The ornamental design for a medal, as shown.

MORRIS SHAPIRO.
